CLAIM

The ornamental design for a display screen or a portion thereof with a graphical user interface as shown and described.

DESCRIPTION

The sole FIGURE is a front view of the display screen or a portion thereof with a graphical user interface.

The outer dot-dash-dot broken lines show a display screen or a portion thereof and are for the purpose of illustrating environment and form no part of the claimed design. The broken lines show portions of the graphical user interface and are for the purpose of illustrating environment and form no part of the claimed design.

1 Claim, 1 Drawing Sheet
